DESIGN FOR A BRILLIANT CUT DIAMOND OR SIMILAR ARTICLE

Phillip Heller, New York, N. Y.

Application July 26, 1944, Serial No. 114,558

Term of patent 14 years

(Cl. D45—1)

To all whom it may concern:

Be it known that I, Phillip Heller, a citizen of the United States, residing at 638 West 160th Street, New York, in the county of New York and State of New York, have invented a new, original, and ornamental Design for a Brilliant Cut Diamond or Similar Article, of which the following is a specification, reference being had

to the accompanying drawing, forming part thereof, in which Fig. 1 is a top plan view of a brilliant cut diamond, showing my new design; and Fig. 2 is a side view thereof.

I claim:

The ornamental design for a brilliant cut diamond or similar article, as shown.

PHILLIP HELLER.
